UNITED STATES PATENT OFFICE.

HERMAN E. BARNES, OF HOUSTON, TEXAS.

LAPPING AND GRINDING MACHINE.

Application filed July 17, 1923. Serial No. 652,051.

To all whom it may concern:

Be it known that I, HERMAN E. BARNES, a citizen of the United States, residing at Houston, in the county of Harris and State of Texas, have invented certain new and useful Improvements in Lapping and Grinding Machines, of which the following is a specification.

This invention relates to certain new and useful improvements in a lapping and grinding machine.

One object of the invention is to provide a machine of the character described specially designed for lapping or grinding the ball joints of locomotive super-heater units so as to give said joints a perfectly smooth oval surface. The machine, however, may be used for any analogous purpose.

Another object of the invention is to provide a machine of the character described, so designed that when set in motion its action will be automatic, and any desired number of said joints may be operated on at the same time.

25 A further feature resides in the provision of a machine of this character which is very simple in construction and consequently may be cheaply and easily constructed and kept in repair.

30 With the above and other objects in view, this invention has particular relation to certain novel features of construction, operation and arrangement of parts, an example of which is given in this specification and 35 illustrated in the accompanying drawings wherein:—

Figure 1 shows a front elevation of the machine.

Figure 2 shows a side view.

40 Figure 3 shows a plan view of the grinder head and spindle.

Figure 4 shows a side view of the spindle connected to the head, the latter being shown in section, and,

45 Figure 5 shows a transverse sectional view of the head, taken on the line 5—5 of Figure 4,

In the drawings the numeral 1 refers to the stand which has a bracket, as 2, fastened 50 to the front side and provided to hold one or more of the tubular super-heater units, as 3, clamped in position to be operated upon. Each unit has a ball joint 4 at one end which must be lapped, or ground to a very smooth 55 surface, for the reason well known to those familiar with the art of locomotive boiler

construction. Rotatably mounted in suitable vertically aligned bearings, carried by the stand, there is one or more vertical shafts, as 5. If more than one shaft 5 is 60 employed these shafts have the spur gears, as 6, keyed thereon, and in mesh with an intermediate gear 7. The lower end of each shaft 6 carries a chuck, as 8, provided to receive the spindle 9, which is operatively 65 connected with, and driven by said chuck. The numeral 10 designates the grinder head which may be formed in sections clamped together by a clamp ring 11. The head has the insert 12, preferably of lead and formed 70 with a socket of the contour of the ball joint desired. The lower end of the spindle has an eccentric ball joint 13 which works in a socket 14 of the head against suitable 75 anti-friction bearings, as 15, therein.

The ball joint to be ground is seated in the socket of the lead insert 12, said socket having been previously lubricated and supplied with a fine abrasive powder. The machine is then started and as the spindle 80 9 rotates, it will impart a uniform gyroscopic motion to the head and the ball joint 4 will be ground to a smooth and uniform oval contour.

The driving mechanism includes a counter 85 shaft 16 mounted to rotate in suitable bearings carried by the stand and fixed upon one end of which is a drive pulley 17. This shaft has a pinion 18 fixed thereon and in mesh with a similar pinion 19 which is fixed 90 on the upper end of the stub shaft whose lower end carries the spur gear 20. This gear 20 is in mesh with, and drives a similar spur gear 21 which is loosely mounted on one of the shafts 5, and which is formed 95 with a clutch member capable of being clutched with and declutched from the clutch 22, splined on said shaft. This clutch may be manipulated in the usual way through the manipulating lever 23 to connect said shaft 5 with, or disconnect it from the driving mechanism.

A tension lever 23 is provided for each drive shaft 5, each lever being pivoted to the upper end of a corresponding standard 24. There is a strong coil spring 25 for each lever, one end of said spring being anchored to the stand and its other end being attached to one end of the corresponding lever. The other end of each lever carries a suitable weight 26 and between said weight and the pivotal mounting of the lever there is a 100 105 110

bracket 27, pivoted to said lever and with which the corresponding shaft 5, has a swivelling connection. The weights exert an endwise pressure through the shafts 5 to 5 the heads 10, thus holding them yieldingly but firmly against the work.

In the construction of my machine I have taken advantage of the fact that the spherical metallic surface to be ground can be made 10 to act upon itself in aiding the grinding operation. The simplicity of this construction is readily apparent because a single grinding cup or head only is necessary, the spherical part to be ground serving in reality 15 as the lower grinding head.

In operation the spherical metallic surface or head, such as the ball joint of a locomotive superheater union connection where it joins the main steam header, is releasably 20 secured in my machine against movement, then the universally movable grinding cup propelled by the crank connected to the main drive shaft is brought into contact with the metallic surface.

25 In effect during the grinding operation the rotation of the drive shaft propels the cup in circular movement around the axis of the spherical head, and the spherical head guides the cup over its own spherical contour. This scope movement of the grinding cup over the spherical metallic surface prevents ring cutting or grooving, which 30 commonly occurs where lapping or grinding is done where the lap or grinding head travels over the work in a constant path; this being due to the ground off metallic particles being carried around continuously in the same path. By my improved construction the sweeping effect of the grinding head 35 over the spherical metallic surface clears the grinding abrasive with the metallic particles therein over the outer circumference of the part to waste, rendering it possible to effect continuous grinding in a power 40 45 operated machine without ring cutting, thereby expediting the grinding time and permitting even unskilled help to operate the apparatus while producing a ground

joint of the highest quality capable of being set into fluid tight engagement without leakage.

It is further desired to bring out the fact in my improved machine that through the automatic clearance effect of the grinding abrasive with its offensive metallic particles, by reason of the scope movement of the grinding cup in the circular movement of the cup around the axis of the spherical surface being ground, that it is possible for the operator to completely finish the grinding of the surface without stoppage of the machine, it only being necessary to raise the revolving grinding cup occasionally from its encompassing engagement with the spherical surface, and then only momentarily in order to apply new abrasive with a swab or brush.

What I claim is:

A machine for grinding a spherical surface upon a metallic head comprising in combination a rotary shaft, means for detachably but rigidly securing an article having a head upon which said surface is to be ground, with the axis of said head axially in line with said shaft, a crank on the end of said shaft and a cup having an hemispherical, internal or concave surface, the counterpart of that desired to be formed, mounted loosely by a universal joint upon the free end of said crank and adapted to be engaged and be guided by said article and caused to have a free rotary motion about an axis of the cup intersecting said joint, as well a gyratory motion of said axis produced by the crank, the radius of the crank and the angle of the axis of the cup being such that the edge of the cup constantly intersects a diameter of the head at right angles to the common axis of the work and the shaft.

In testimony whereof I have signed my name to this specification in the presence of two subscribing witnesses.

HERMAN E. BARNES.
